UNITED STATES PATENT OFFICE.

BENGT M. W. HANSON, OF HARTFORD, CONNECTICUT, ASSIGNOR TO PRATT & WHITNEY COMPANY, OF NEW YORK, N. Y., A CORPORATION OF NEW JERSEY.

WHEEL-DRESSING MECHANISM.

Application filed July 31, 1918. Serial No. 247,637.

To all whom it may concern:

Be it known that I, BENGT M. W. HANSON, a citizen of the United States, residing at Hartford, in the county of Hartford and 5 State of Connecticut, have invented certain new and useful Improvements in Wheel-Dressing Mechanism, of which the following is a specification.

The wheel dressing mechanism embodying 10 the invention is particularly well adapted for use with or as a part of a grinding machine of the type set forth in my copending applications for grinding machines, Serial No. 247,632 and Serial No. 247,634 both filed 15 on even date herewith. It will be understood, however, that the wheel dressing mechanism is not limited to use in machines of this type but is of general application.

One of the objects of the invention is to 20 provide a wheel dressing mechanism having improved devices whereby it may be operated by power. Another object of the invention is to provide in combination with the power operating devices improved means 25 whereby the dressing tool may be controlled automatically and manually. A further object of the invention is to provide improved means, including a former, whereby the dressing tool may be guided to dress 30 the wheel to any desired contour. Further objects of the invention will be apparent from the following specification and claims.

In the accompanying drawings I have 35 illustrated the invention applied to a grinding machine which is similar in many respects to the machines shown in my aforesaid copending applications. It will be understood, however, that the drawings are intended to be merely illustrative and are not to be construed as defining or limiting the scope of the invention, the accompanying claims being relied upon for that purpose.

Of the drawings:

45 Fig. 1 is a plan view showing the wheel dressing mechanism and some of the parts of the grinding machine, other parts being removed for the sake of clearness.

Fig. 2 is a transverse vertical sectional

view through the grinding machine showing 50 the wheel dressing mechanism.

Fig. 3 is a plan view of the devices which support and guide the wheel dressing tool.

Fig. 4 is a sectional view taken along the line 4-4 of Fig. 3. 55

Fig. 5 is a detail view showing the former.

The grinding machine is provided with a main frame 1 and a grinding wheel 2 which is preferably mounted for rotation about a fixed horizontal axis. The wheel is carried 60 by a spindle 3 which is supported in bearings 4 and 5. The work to be ground is indicated at A and this is supported and rotated by suitable devices carried by a work supporting table 6. This table is movable 65 toward and from the wheel under the control of suitable feeding mechanism indicated as a whole by 7. Preferably the table 6 is mounted on a swinging auxiliary frame 8 which is pivoted to the main frame at 9. 70 For holding the work in engagement with the grinding wheel and for preventing deflection, one or more back-rests are preferably provided such as shown at 10.

The surface of the grinding wheel 2 must 75 conform to the shape of the work to be ground. For cylindrical or uniformly tapered work the wheel is preferably cylindrical throughout. For work other than straight tapered work which varies in diameter the wheel must be dressed to a contour corresponding to the contour of the work. In order that the dressing of the wheel, whether for cylindrical grinding or for contour grinding, may be easily and accurately effected, I provide a special wheel dressing mechanism which constitutes a permanent part of the machine. It is to this wheel dressing mechanism that my present invention particularly relates. 80

Formed in the bottom of the table 6 is a longitudinal dovetailed recess which forms a guideway. Fitted in this recess for sliding movement is a slide 11. The slide 11 carries a wheel dressing tool 12 of any usual 85 or preferred construction. The slide is adapted to be moved longitudinally of the table in the space between the bottom of

the table and the top of the swinging frame 3. When it is so moved the tool 12 travels along the surface of the wheel to properly dress and true it. In order that the wheel 5 may be dressed to any desired contour the tool 12 is not carried directly by the slide 11 but is mounted on a second slide 13 which is transversely movable with respect to the slide 11. I provide means whereby the slide 10 13 may be moved forward or backward simultaneously with the longitudinal movement to enable the tool to dress the wheel to the required contour. This means comprises a former plate or bar 14 (shown in detail in Fig. 5) which is secured in a rabbet formed at the lower front edge of the table. The front edge of the former is shaped to conform to the required contour of the wheel and it will be understood that the former 14 20 can be removed and another former substituted having a different contour. The slide 13 is provided with means for engaging the former 14, this means preferably comprising a bracket 15 projecting upward from the front end of the slide and a roller 16 carried by the bracket. Coil springs 17 are provided for pressing the slide rearward and for holding the roller in engagement with the former 14. As clearly shown in Fig. 2, the 25 springs 17 are seated in the recesses in the slide 13, the front outer ends of the springs reacting against an abutment secured to the slide 11. Preferably there is a cover 18 secured to the table and extending over the former and the roller to protect them and 30 exclude dirt.

In order that the wheel may be given exactly the same contour as the former, it is necessary for the point of the tool to move 35 in a plane which passes through the axis of the wheel. As shown in Fig. 2, the swinging frame 8 is so positioned that the slide 13 is horizontal, the point of the tool 12 being at the same level as the axis of the wheel. After the wheel has been worn to a smaller 40 diameter, the tool 12 must be moved rearward in order to engage the wheel. This rearward movement might be effected by swinging the frame 8, but obviously this 45 swinging movement would incline the slide 13 so that the tool 12 would move in a plane not passing through the wheel axis. The result would be that the contour of the wheel would not conform exactly to the contour 50 of the former. When the required contour is such that the variations in the diameter of the wheel are slight, the inaccuracy resulting from the movement above described would probably be so small as to be negligible; but, in order that the machine may be 55 adapted for the dressing of wheels to contours causing widely different diameters, I prefer to provide means whereby the tool 12 may be adjusted without moving the frame 60 8 or inclining the slide 13. As illustrated,

the tool 12 is connected with the slide 13 by means of a second transverse slide 19. This slide is movable under the control of a screw 20 provided with a handle 21. Preferably 65 graduations are provided at 22 whereby the amount of movement of the screw may be observed. By means of the slide 19 the tool 12 can be moved to compensate for differences in diameter of the wheel without moving the frame 8 in such a way as to incline 70 the slide 13.

For moving the slide 11 longitudinally of the table, I preferably provide a longitudinal threaded shaft or screw 23 which is mounted at its ends in suitable bearings in 75 the table. This screw extends through an aperture in the slide 11 and has threaded engagement therewith. It will be seen that when the screw is turned the slide will be moved longitudinally, carrying with it the 80 slides 13 and 19 which are at the same time moved forward or backward under the control of the former 14.

I prefer to provide power mechanism for 85 rotating the threaded shaft or screw 23. In the drawings I have illustrated a mechanism for this purpose such as is shown in my co-pending application Serial No. 247,632, but it will be understood that, if preferred, a mechanism such as shown in my application 90 Serial No. 247,634 may be used.

As illustrated, a suitable housing 24 is secured to the table at the right-hand end and the shaft 23 is extended into the housing. Rotatably mounted on the shaft within the 95 housing are two gears 25 and 26. Splined to the shaft between the gears is an annularly grooved clutch collar 27. This collar has teeth at one side adapted to engage pins carried by the gear 25 and has teeth at the 100 other side adapted to engage pins carried by the gear 26. Rotatably mounted in the housing is a shaft 28 carrying a belt pulley 29 at the right-hand end. The shaft 28 carries a pinion 30 which meshes with the gear 105 26 and it also carries a gear 31 which meshes with an idler gear 32, the idler gear in turn 110 meshing with the aforesaid gear 25.

Rotatably mounted at the pivotal axis of the swinging frame 8 is a longitudinal shaft 115 33. Connected with the shaft 33 at its left-hand end is a belt pulley 34 which is in register with a belt pulley 35 carried by the spindle 3. A belt 36 passes over and connects the two pulleys 34 and 35. At its 120 right-hand end the shaft 33 carries a belt pulley 37 which is in register with the aforesaid pulley 29. A belt 38 passes over and connects the two pulleys 37 and 29. By means of the mechanism described the shaft 125 28 is driven continuously and is movable with the swinging frame without interrupting or disturbing the power connection.

For operating the clutch collar 27 there is provided a forked lever 39 mounted for 130

movement about a vertical axis at 40. Pivoted to the lever 39 are rectangular shoes which fit the groove in the collar 27. Connected with the lever is a second lever 41 which extends forward. To this lever 41 there is pivoted a rod 42 which extends across the front of the machine and is supported by bearings at 43 and 44. Carried by the rod 42 are handles 45, 45 by means of which the rod can be moved longitudinally to shift the clutch. When the clutch is engaged with the gear 26 the screw 23 is rotated slowly in the direction to move the dressing tool from left to right across the wheel.

When the clutch is shifted to engage the gear 25 the dressing tool is moved rapidly in the opposite direction. Preferably the rod 42 is provided with collars 46 and 47 which are adapted to be engaged by the slide 13 to automatically shift the rod and prevent movement of the dressing tool beyond a predetermined limit in either direction. One or the other or both of the collars 25 may be adjustable along the rod, if desired.

As will be apparent from the foregoing description, the machine is primarily intended for the grinding of a large number of similar pieces of work. In the preliminary adapting and adjusting of the machine for the work to be done, it is first necessary to construct a former 14 having its effective edge shaped to conform to the required contour of the finished work.

When such a former has been constructed it is put in place in the machine and is used for dressing the grinding wheel. For the dressing operation the frame 8 is adjusted to bring the slide 13 into a level position as shown in Fig. 2. Assuming that the slide 11 is in its left-hand position, the operator, by means of the handle 21 moves the slide 19 far enough rearward to bring the tool 12 into engagement with the wheel.

Then the operator, by means of the rod 42, starts the movement of the slide 11 which carries the tool 12 toward the right. During this movement the position of the tool 12 is controlled by the former 14, and, because of the springs 17, the pressure of the tool against the wheel is definitely limited. After movement across the wheel the slide is automatically stopped by the right-hand collar 46. In initially dressing the wheel it

55 may be necessary to move the tool across it several times. When this is required the operator by means of the rod 42, shifts the clutch 27 to move the slide 11 toward the left. During the movement toward the left 60 the tool may remain in engagement with the wheel, but it is preferably withdrawn either by moving the frame 8 or by moving the slide 19. The slide 11 is automatically stopped by the left-hand collar 47. Then 65 the tool can be moved toward the right as

before, and this operation can be repeated until the wheel has assumed a contour corresponding exactly to that of the former 14.

What I claim is:

1. The combination of a rotatable grinding wheel, a work support adjacent the wheel, a wheel dressing tool, a tool carrying slide movable longitudinally along the face of the wheel relatively to the work support, a rotatable screw for moving the slide, and power actuated mechanism for rotating the screw in either direction. 76

2. The combination of a rotatable grinding wheel, a work support adjacent the wheel, a wheel dressing tool, a tool carrying slide movable longitudinally along the face of the wheel relatively to the work support, a rotatable screw for moving the slide, power actuated mechanism for rotating the screw in either direction, and 80 manually operable means for controlling the power actuated mechanism to start, stop and reverse the screw. 35

3. The combination of a rotatable grinding wheel, a work support adjacent the wheel, a wheel dressing tool, a tool carrying slide movable longitudinally along the face of the wheel relatively to the work support, power actuated mechanism for moving the slide in either direction, and 90 means comprising a horizontal rod extending along the front of the work support for starting and stopping the power actuated mechanism. 95

4. The combination of a rotatable grinding wheel, a work support adjacent the wheel, a wheel dressing tool, a tool carrying slide movable longitudinally along the face of the wheel relatively to the work support, power actuated mechanism for moving the slide, and adjustable means for automatically stopping the slide after movement to a predetermined extent. 100

5. The combination of a rotatable grinding wheel, a work support adjacent the wheel, a wheel dressing tool, a tool carrying slide movable longitudinally along the face of the wheel relatively to the work support, power actuated mechanism for moving the slide in either direction along the 110 face of the wheel, and means for automatically stopping the slide after movement to any predetermined variable extent in either direction. 115

6. The combination of a rotatable grinding wheel, a slide movable longitudinally along the face of the wheel, a second slide carried by the first slide and movable transversely thereof, a wheel dressing tool carried by the second slide, a former for moving the second slide toward or from the wheel axis as the slide is moved longitudinally, a third slide carried by the second slide and movable parallelly therewith independently of the former toward or from the 125 130

25
wheel axis, and a wheel dressing tool carried by the third slide.

7. The combination of a rotatable grinding wheel, a work support mounted for pivotal movement about an axis parallel with the axis of the wheel, a wheel dressing tool, a tool carrying slide movable longitudinally of the work support, a former for moving

the tool toward or from the wheel axis as the slide is moved longitudinally, and means supplemental to the former for moving the tool toward or from the wheel axis independently of the work support.

5 In testimony whereof, I hereto affix my signature.

BENGT M. W. HANSON.
